ATTORNEY.

UNITED STATES PATENT OFFICE.

BERNARD BRIODY, OF CHICAGO, ILLINOIS, ASSIGNEE TO TRUSCON STEEL COMPANY,
OF YOUNGSTOWN, OHIO, A CORPORATION OF MICHIGAN.

ROADWAY JOINT.

Application filed February 23, 1922. Serial No. 538,546.

To all whom it may concern:

Be it known that I, BERNARD BRIODY, a citizen of the United States, and residing at Chicago, in the county of Cook and State of Illinois, have invented a new and Improved Roadway Joint, of which the following is a specification.

This invention relates to concrete roadways and especially to means for preventing the pavement from breaking along irregular lines substantially longitudinally of the roadway, and its object is to provide means which will cause the roadway to crack along a central line longitudinally of the roadway when the stresses set up in the concrete are greater than can be resisted by the strength of the roadway.

This invention consists in a strip embedded vertically in, and extending longitudinally of a concrete roadway, and being preferably of less depth than the concrete slab and having its upper edge a distance below the upper surface of the slab. It further consists in longitudinally corrugating the strip in order to provide for a tongue-and-groove joint between the adjacent edges of the two sections of the roadway slab. It also consists in reinforcing rods for the slabs extending transversely of the roadway through holes in the metal strip. It also consists in the details of construction illustrated in the accompanying drawing and particularly pointed out in the claims.

In the accompanying drawing, Fig. 1 is a plan of a piece of roadway provided with my improved contraction joint. Fig. 2 is a vertical longitudinal section of the central part thereof. Fig. 3 is a section on the line 3-3 of Fig. 2.

Similar reference characters refer to like parts throughout the several views.

The roadway 1 shown in the drawing may have curbs 2, although these may be omitted. It is formed by spreading a layer of concrete 3 over the sub-base 4 in the usual manner. Embedded in the concrete longitudinally of the roadway, and preferably along the middle thereof, is a strip formed from sheet metal, paper, or other stiff material with

vertical portions 5, 6 and 7, and inclined portions 8 and 9. This corrugated strip is preferably in sections whose ends overlap, and these ends may be connected by one of the supporting pins or stakes 10, which extend through holes in the portions 8 and 9 at intervals to position the strips. The strips are preferably of thin sheet steel.

This strip preferably extends up from the bottom of the concrete to within about one half inch from the finished upper surface thereof. Rods 12 are preferably extended through holes in the middle portions, 6 of the corrugations or channels of these strips at regular intervals and are embedded in the concrete to hold the two sides of the roadway in proper relation to each other. If there is any movement of the roadway by reason of frosts or otherwise, a crack will be formed along its center, but the tongue 13 along the inner edge of one side of the roadway extends into the channel formed in the inner edge of the other side of the roadway by means of the parts 8, 6 and 9 of the strips, and this tongue-and-groove joint and the rods 12 cause the upper surface of the roadway to remain flat and to return to its original position after the cause of the movement has passed. The shape of this channel is immaterial so long as the interlock is provided.

The depth and thickness of the strip and the form of its corrugation may be varied as desired by those skilled in the art without departing from the spirit of my invention as set forth in the following claims.

I claim:

1. A concrete roadway, a channel-shaped strip of sheet metal embedded therein along its middle line and formed with holes, and tension rods embedded in the concrete transversely to the roadway and passing through the holes in the strip.

2. A concrete roadway, a strip of metal embedded therein below the upper surface of the roadway, and tension bars passing through the strip into concrete on both sides of the strip the length of said bars being more than half the width of the roadway.

3. A roadway comprising two parts, joining along the middle of the roadway, one of said parts having a longitudinal channel and the other having a tongue extending into said channel, and metal rods extending across the joint transversely of the roadway.

4. A roadway comprising two parts joining along the middle of the roadway, one of

said parts having a longitudinal groove in its inner edge and the other having a tongue 10 extending into said groove, a sheet metal facing for said groove, and rods extending across the joint transversely of the roadway through said sheet metal.

BERNARD BRIODY.
